CHARLES L. GOODSPED, OF GLEN BLOC, NEW JERSEY, ASSIGNOR TO AVIS L. GOODSPED, OF RIDGEWOOD, NEW JERSEY

ELECTRIC PLUG

Application filed February 24, 1928. Serial No. 256,639.

This invention relates to electrical extension cord push plugs, and comprehends means constituting a part of the plug for facilitating its disconnection from an outlet socket.

It is a well-known fact that push plugs tend to stick in the sockets, and due to the fact that said plugs are constructed in such a manner as to afford no means for facilitating their withdrawal or disconnection from the sockets with which they are associated, it is a common practice to employ the extension cord as a means for withdrawing the plug from the socket. This results in breakage of the cord, causing short circuits in addition to subjecting the terminal posts to strain which eventually renders the plug unfit for use.

The present invention comprehends a simple, convenient, inexpensive and efficient means for facilitating the withdrawal and disconnection of the plug from its socket without injury thereto or to the extension cord which is carried thereby.

Furthermore, the invention comprehends a means for facilitating the disconnection of an extension cord push plug from a socket which effects a direct outward movement of the plug from the socket so as to relieve the connecting elements of lateral thrusts which tend to injure the structure.

With the above recited and other objects in view, reference is had to the following description and accompanying drawings in which there is exhibited one example or embodiment of the invention while the appended claims define the actual scope of the invention.

In the drawings—

Figure 1 is a side view with parts in section, illustrating the plug in full and dotted lines, respectively, in the disconnected and connected positions;

Fig. 2 is a sectional view through the plug and socket illustrating the plug in its connected relation to the socket;

Fig. 3 is a plan view of the pull element disassociated from the plug;

Fig. 4 is a cross-sectional view of the plunger or stem;

Fig. 5 is a side view of the combined stem

bearing and pull element attaching member removed from the plug.

Referring to the drawings by characters of reference A designates an outlet socket of any approved type, which is provided with female contact elements B disposed in alignment with apertures C in the wall or casing of the socket, through which the contact legs D of the plug E are adapted to be inserted and engaged with the female contact elements B. The plug E is provided with a threaded axial bore 10, which communicates with the recess 11 in the inner face of the plug within which the contact legs D are attached in the usual manner and with which the terminals of the extension cord 12 are connected.

The invention includes an exteriorly threaded thimble 13 which is threaded into the bore 10 and which is provided at its outer end with an annular outwardly projecting flange 14. A ring or annulus 15 having diametrically disposed finger-engaging hooks 16 is attached to the plug body by clamping of the ring or annulus 15 between the flange 14 and the outer end of the plug. A plunger or stem 17 extends through the thimble 13, which acts as a bearing therefor, thereby mounting the plunger or stem in the plug for axial movement with respect thereto. The plunger or stem is preferably of tubular formation and is closed at its outer end by a manipulating head 18 and at its inner end by a solid extremity 19. The plunger or stem is preferably formed with a slot 20 in its wall, through which the extension cord 12 extends.

In practice, with the stem or plunger 17 in the position illustrated in Fig. 1, the plug is pushed into the socket so that the contact legs D are frictionally engaged with the female contact elements B. During this operation, the inner slot terminal 19 of the stem or plunger bears against the central portion of the outer wall of the socket so that the plug E moves axially thereof and relatively thereto to the position illustrated in dotted lines in Fig. 1 or the position illustrated in Fig. 2. This causes the plunger or stem to project outwardly an appreciable distance from

the outer end of the socket so that when it is desired to disconnect the plug from the socket, the index and middle fingers are engaged around the hooks or clips 16 and the thimble 5 bears upon the manipulating head 18 of the stem. By moving the plug outwardly on the stem or plunger by pulling the fingers toward the thumb, it is obvious that the plunger acts as a guide for causing the plug to 10 move directly outwardly to prevent lateral movement which tends to injure the structure of both the plug and socket. In order to limit the relative movement of the plug with respect to the stem or plunger, the 15 plunger 17 is formed with peripheral beads 21 and 22 which coact with the thimble 13.

I claim:

1. An electrical extension cord push plug, including means carried thereby for facilitating the disconnection of the plug from its socket, said means consisting of a stem extending axially through the plug and adapted to bear at its inner end upon the socket and finger engaging elements carried by the plug, a bushing through which the stem extends having threaded connection with the plug body and a head at one end of said bushing for clamping the finger engaging elements to the plug body.
2. The combination, with an electrical extension cord push plug, of means carried by the plug body for facilitating the disconnection of the plug from a socket, said means comprising a ring having diametrically disposed finger engaging pull clips, a bushing threaded into the plug body and extending through the ring for attaching the same thereto, and a thumb engaging plunger mounted for axial movement through the bushing and plug body and designed to bear at its inner end upon the central portion of the socket to serve as a guide for causing a direct outward movement of the plug body from the socket.
3. Signed at New York, in the county of New York and State of New York this 17th day of February, A. D. 1928.

CHARLES L. GOODSPED.
